UTILITY DEVICE

John E. Borah, Mishawaka, Ind.

Application September 23, 1957, Serial No. 685,700

8 Claims. (Cl. 45—28)

The present invention relates to an article retaining device and more particularly to a device or holder which is attached to a supporting surface by suction.

One of the principal objects of the present invention is to provide a device adapted to be secured to a supporting surface and form an effective seal therewith at or near the periphery of the device.

Another object of the invention is to provide a device secured to a supporting surface by suction and having two or more suction chambers of different sizes and relative location for attaching the device to the surface.

A further object of the invention is to provide a device of the aforesaid type having a relatively large chamber on the underside thereof sealed at its outside edge by a circumferential sealing ring secured to the body of the device.

Still another object is to provide a utility holder for use around the lavatory, bath tub and kitchen sink for holding bars of soap and other articles, having a plurality of sumps for catching the water draining from the articles and being secured to a supporting surface by one or more suction cups.

Another object is to provide an easily cleaned soap dish or the like which can be readily attached to and detached from a supporting surface and which permits a bar of soap regardless of its shape to drain and dry thoroughly.

Another object is to provide a device of the aforesaid type of a one piece construction, which is relatively easy to fabricate with standard equipment and which can easily be mounted on and firmly attached to small uneven supporting surfaces.

Additional objects and advantages will become apparent from the following description and accompanying drawings, wherein:

Figure 1 is a top plan view of a soap holder or the like embodying my invention;

Figure 2 is a vertical cross sectional view taken on line 2—2 of the holder shown in Figure 1;

Figure 3 is a bottom view of the holder shown in Figures 1 and 2;

Figures 4 and 5 are vertical cross sectional views of two modified forms of utility holders embodying my invention, the first figure showing the holder in its original shape detached from a supporting surface and the second figure showing the holder secured to a supporting surface;

Figures 6 and 7 are vertical cross sectional views of another modified form of utility holder;

Figure 8 is an elevational view of a part of the modified form of the device illustrated in Figures 6 and 7;

Figure 9 is a vertical cross sectional view of a further modified form of my invention; and

Figure 10 is a bottom view of the device shown in Figure 9.

My utility holder 18, shown in Figures 1, 2, and 3, consists of a disc shaped body 20 of rubber or rubber-

2

like material having a concave upper surface 22 draining to a centrally located cup shaped sump 24 for catching and retaining the water dripping from a bar of soap placed on the holder. In order to hold the bar of soap 5 on edge so that the water can drain effectively therefrom and flow into sump 24, and so that the bar can be easily grasped by the user to lift it from the holder, four posts 26 are provided on the concave upper surface to hold the bar on one of its edges. These posts are spaced 10 equally around the concave surface and at sufficient distance from the center that a new bar of soap can fit between the posts and rest on projections 28 arranged in a circle near the edge of the sump or on radially arranged ribs 30 disposed between the posts. The projections and 15 ribs contact the bottom of the soap in only limited areas and hold the soap off the upper surface so that water can drain under the bar. This permits the soap to dry over its entire surface and prevents the formation of thick soap solutions along the lower edge of the bar and on the 20 upper surface of the holder. As the bar becomes thin and small from usage the posts may be spaced too far apart to hold the bar on one of its edges. The bar is then leaned against two of the posts and projections 28 and/or ribs 30, depending on the shape of the bar, prevent the 25 bar from slipping from its vertical position. If the bar of soap, is rectangular in shape the lower corners rest on the radial ribs, whereas if the bar is oval or round in shape it rests on the projections; the position assumed by the oval bar is illustrated by broken lines in Figure 2 30 by numeral 32. Four radial grooves 36 extending from the outer edge of the concave surface and terminating at sump 24 facilitate draining of the soapy water into the sump and thorough drying of the soap thereafter by permitting the air to circulate around and under the 35 soap. An upstanding peripheral annular flange 38 is preferably provided on the upper surface of the body to prevent the soapy water solution from wet bars of soap from accidentally spilling over the outside edge of the holder. The posts 26 are described in greater detail and 40 claimed in my copending application Serial No. 677,426 filed August 12, 1957.

The underside of body 20 is generally concave forming a chamber 39 and has attached thereto a centrally located suction cup 40 supported by walls 41 of sump 24. 45 The outside wall of the body surrounding chamber 39 is provided with an annular groove 42 near the lower edge thereof which forms a flexible outwardly and downwardly extending sealing flange 43 which is adapted to contact the supporting surface for the holder to form an effective 50 seal therewith. When the holder is pressed downwardly to engage suction cup 40 with the supporting surface, flange 43 spreads outwardly, firmly engaging the surface with a substantial portion of the internal wall thereof, thus forming a water tight seal between the flange and 55 surface. Since the flange is relatively narrow and flexible and the body of the holder is relatively thick and rigid, particularly away from the center, substantially all of the down force exerted by cup 40 is transmitted to the flange where it is used to form the seal. Flange 60 43 also gives stability to body 20 and prevents the holder from rocking and tilting.

From the view in Figure 2 it is seen that chamber 39 is nearly as large in diameter as the body 20 and is substantially larger than suction cup 40, thus leaving a relatively large unoccupied space beneath the body between cup 40 and the internal wall of flange 43. The upper surface 22 contains an annular groove 44 surrounding projections 28 and intersecting radial grooves 36. This 65 annular groove is connected by a plurality of holes 46 with chamber 39 in the space external of suction cup 40. With this construction the water draining from the soap 70

on the upper surface normally flows down said surface into groove 44 or down grooves 36 into sump 24 where it will remain until the holder is cleansed. However, in the event the sump becomes full, any additional water flows into annular groove 44, thence through holes 46 into chamber 39 where it is retained by the seal formed by the sealing ring of flange 43 engaging the surface supporting the holder. The water which drains into chamber 39 is confined in the space between suction cup 40 and flange 43 and keeps the surfaces adjacent the lips of the suction cup and the flange moist so that a more effective gripping action and seal are maintained.

It is noted that sump 24 occupies the space normally used merely as a stem or support for a suction cup, hence the present design utilizes space to catch the water draining from the soap which would normally be dead weight in such a structure. The double sump arrangement, i. e. sump 24 and chamber 39, permits continued use of the holder without soiling the surface on which the holder is placed if care is used to clean the holder at frequent intervals; however, if it is cleaned only occasionally, the overflow is contained in chamber 39 by sealing flange 43 and is prevented from soiling any part of the supporting surface exposed to sight.

In the modifications shown in Figure 4 and subsequent figures, a number of the features associated therewith are identical in construction and function as those features of the embodiment just described; therefore, like reference characters have been applied to like parts and a detailed description of those parts omitted. The upper surface 22 of the holder shown in Figure 4 is concave in shape and contains posts 26, projections 28, ridges 30 and radial grooves 36. The underside of the body of this modification is concave and terminates in flange 43 and has mounted thereon four suction cups 50 connected to the body by necks 52. These cups are spaced equally from the center and are equally spaced from one another, similar in arrangement to the small suction cups shown in Figures 9 and 10. The lower edge of the flange 43 engages and forms an effective seal with the supporting surface when the suction cups are pressed into gripping position on the supporting surface. In this modification the sump 24 and suction cup 40 of the preceding modification have been removed and an opening 60 is employed instead for connecting the upper surface of the holder with a chamber 39 defined by the lower surface of body 20, flange 43 and its supporting surface. An annular ledge 61 is interposed between projections 28 and hole 60 and is on the same plane as the lower ends of grooves 36. With this construction the soapy water which drains from the bar of soap placed in the holder flows down the upper concave surface 22, through opening 60 into chamber 39 where it is retained until the holder is removed from the supporting surface for cleaning. While the basic concept of forming a water retaining chamber beneath the soap holder using the supporting surface as the bottom of the chamber, sealing the chamber with an annular flange on the bottom of the holder and a suction cup in the chamber for attaching the holder to the supporting surface is disclosed and claimed in my copending application mentioned supra, the present invention employs a distinct sealing flange 43 formed by groove 42 with an annular body section 62 thereabove in order to concentrate the forces securing the holder to the supporting surface at the flange so that an effective seal will be maintained between the underside of the flange and said surface. The water draining into chamber 39 surrounds the lower edge of the suction cups and the adjacent area of the supporting surface and thereby assists in forming and maintaining effective gripping action by the cups.

In the soap holder shown in Figure 5, the upper surface has been provided with a series of annular steps 66 which provide thin edges 68 for contacting the bar of soap only at spaced points and grooves 70 for receiving

the water draining from the soap. While a plain concave upper surface may be satisfactory for some uses, the space provided under the soap by the grooves permits the soap to drain and dry more thoroughly. The bottom side of the holder is identical to the one shown in Figure 4 and is shown in its gripping position with a supporting surface 72. In this figure the flaring outwardly of sealing flange 43 and the engagement of the internal surface thereof with the supporting surface can be clearly seen at numeral 74.

The utility holder shown in Figures 6 and 7 is similar in many respects to the embodiment shown in Figures 1 through 3, hence like numerals will be used for like parts. In this embodiment my utility holder 18 is placed in a receptacle 80 in order to take advantage of the large water receiving capacity of chamber 39 without permitting the water to come in contact with the supporting surface. Holder 18 is the same as the one shown in Figures 1, 2 and 3 with the exception that the central sump 24 and suction cup 40 have been removed, leaving a hole 82 in their place. Receptacle 80 as shown in Figures 6, 7 and 8 consists of a disc shaped body 84 having upstanding sides 86 and an annular groove 42 near the lower edge and flexible outwardly and downwardly extending sealing flange 43. The bottom surface of body 84 is concave and in cooperation with flange 43 forms a suction cup for securing the receptacle to a supporting surface. In assembling holder 18 and receptacle 80 the holder is placed in the receptacle with flange 43 of the holder resting on the upper surface 85 of body 84. In this arrangement flange 43 of the holder is not depressed and the holder merely rests on the upper surface of the receptacle within the space defined by walls 86. Figure 6 shows the two units assembled and the shape which they assume before the lower unit 80 is secured to a supporting surface. Figure 7 shows the two units assembled and the lower unit gripping a supporting surface 88, with the central portion of body 84 depressed and flange 43 of said unit distended and firmly engaging and forming an effective seal with the supporting surface. With the holder of this modification, after the soap has been used, it is placed on edge on the upper surface and is held in a substantially vertical position by posts 26 and off surface 22 by projections 28. The water draining from the soap flows down surface 22 through hole 82 into chamber 39 where it is retained until the two units are cleaned.

The holder shown in Figures 9 and 10 is similar in many respects to the holder shown in the preceding figures, the features on the upper surface being the same as those shown in the embodiments of Figures 1 and 6, with the exception that only the single sump 24 is used to catch the water draining from the article placed in the holder. Holes 46 have been omitted, thus leaving chamber 39 completely enclosed when the holder is placed on a supporting surface. The lower side of this holder is provided with three distinct suction means so that an effective gripping action can be obtained on either large or small supporting surfaces. Chamber 39 being 60 completely enclosed forms an effective suction cup in conjunction with yieldable flange 43 and alone is capable of securing the holder firmly to a relatively large and smooth supporting surface. The center suction cup 40 being substantially smaller than one formed by chamber 39 will effectively secure the holder to a relatively small supporting surface. In addition to these two suction cups, four small suction cups 90 are attached to the bottom surface of the body and are equally spaced from the center and from each other. These small suction cups permit the holder to be secured to small and uneven supporting surfaces since the individual cups not only require merely a small surface to form an effective grip but also an effective grip can be obtained with only one or two of the cups if a larger suitable surface is unavailable.

The holders and units described herein are usually constructed of rubber or rubber-like material; however, combinations of materials can be used if desired. While a number of important features on both the upper and lower sides of the utility holder and of the lower unit of the embodiment shown in Figures 6, 7 and 8 are described herein, various other combinations and changes and modifications in the features themselves can be made without departing from the scope of the present invention.

I claim:

1. A device for holding and draining soap, comprising a disc shaped body having a concave upper surface and a concave lower surface, a water receiving means in the center of said upper surface, a plurality of upstanding posts spaced from one another on said upper surface, a hole connecting said upper surface with the underside of said body, a yieldable flange at the margin of said concave lower surface, an annular groove in the periphery of said body in close proximity to said flange, and a suction cup attached to said lower surface beneath said water receiving means.

2. A utility holder, comprising a disc shaped body having a concave upper surface, a concave lower surface, a hole connecting said upper surface with the underside of said body, a flexible flange at the margin of said concave lower surface, an annular groove in the periphery of said body in close proximity to said flange, and a plurality of relatively small suction cups attached to said lower surface and equally spaced from the center.

3. A utility holder, comprising a disc shaped body having a concave upper surface, a concave lower surface, grooves and ridges on said upper surface, a central hole connecting said upper surface with the underside of said body, a flexible flange at the margin of said concave lower surface, an annular groove in the periphery of said body in close proximity to said flange, and a plurality of relatively small suction cups attached to said lower surface and equally spaced from the center.

4. A device adapted to be secured to a supporting surface, comprising a disc shaped body having a concave lower surface, a highly flexible flange at the margin of said concave lower surface, a shallow annular groove

in the periphery of said body, in close proximity to said flange, and a suction cup attached to said lower surface.

5. A device for holding and draining soap, comprising a disc-shaped body having a concave upper surface and a concave lower surface, four flexible posts spaced from one another on said upper surface, said posts being tapered inwardly toward the top, a hole connecting the lowest portion of said upper surface with the under side of said body, a yieldable flange at the margin of said concave lower surface, an annular groove in the periphery of said body in close proximity to said flange, and four suction cups integrally attached to said lower surface for engaging a surface on which the device is placed.

10 15 6. A device for holding and draining soap, comprising a disc-shaped body having a concave upper surface, a plurality of flexible posts spaced from one another on said upper surface, a hole connecting the lowest portion of said upper surface with the under side of said body, and a plurality of suction cups integrally attached to said lower surface for engaging a surface on which the device is placed.

20 25 7. A utility holder, comprising a disc-shaped body having a concave upper surface, four equally spaced flexible posts on said surface, said posts being tapered inwardly toward the top and extending upwardly and outwardly from the upper surface of said body, and a suction cup attached to the lower surface of said body for engaging a surface on which the holder is placed.

30 8. A utility holder, comprising a body having a concave upper surface, a plurality of flexible elongated posts spaced from one another on said upper surface, and a suction cup attached to the lower surface of said body for engaging a surface on which the holder is used.
